APPLIANCE BASE

William H. Fischer, St. Louis, Mo., assignor to
 Knapp-Monarch Company, St. Louis, Mo., a
 corporation of Missouri

Application May 24, 1937, Serial No. 144,460

8 Claims. (Cl. 65—53)

One object of my present invention is to provide a supporting base for electrical appliances, such as sandwich toasters and the like, having a novel and simple means for supporting the plate above a table top or other supporting surface.

A further object is to provide a supporting means for a sheet metal plate-like appliance base comprising elongated elements so associated with the ends of the base that they form continuations thereof, and to provide means for spacing the plate above a table top and also ledges or flanges under which the user may engage the ends of his fingers for lifting the appliance without coming in contact with any of the heated portion of the appliance.

A further object is to provide an inexpensive supporting means for a base plate comprising elongated elements having means at least at their ends projecting under the base plate to support it, the base plate having flanges which partially encircle the projecting means to thereby retain the base plate and its supporting elements assembled relative to each other.

Another object is to provide supporting members for a base plate having hooked flanges which reinforce two of its edges, the supporting members being adaptable to support and reinforce the other two edges thereof.

With these and other objects in view, my invention consists in the construction, arrangement and combination of the various parts of my appliance base, whereby the objects contemplated are attained, as hereinafter more fully set forth, pointed out in my claims, and illustrated in the accompanying drawing, in which:

Figure 1 is a front elevation of an electrical appliance, showing my base plate connected therewith.

Figure 2 is an enlarged plan view of one corner of the appliance base.

Figure 3 is a sectional view on the line 3—3 of Figure 2, showing the assembly of the base plate and supporting member relative to each other.

Figure 4 is a sectional view on the line 4—4 of Figure 3, showing how a hooked flange of the base plate coats with a portion of the supporting member to partially encircle it and thus position the two relative to each other.

Figure 5 is a perspective view of a slightly modified construction of the supporting element.

Figure 6 is a perspective view of another modified supporting element.

Figure 7 is a view similar to Figure 4, showing

the coaction of the base plate with the form of supporting element shown in Figure 6; and

Figure 8 is a sectional view on the line 8—8 of Figure 7, the portion 8a of Figure 8, being taken on the line 8a—8a of Figure 7.

On the accompanying drawing throughout the various figures thereof, I have used the reference numeral 10 to indicate a supporting base in the form of a plate of sheet metal, on which an electrical appliance A (see Figure 1) is mounted. 10 For instance, the bottom of the appliance A and the top of the base 10 may be provided with projecting bosses 11, suitably secured together and serving the purpose of spacing the appliance from the base plate. 15

The base plate 10 is reinforced along the side edges thereof by flanges 12. The flanges 12 are preferably U-shaped or hooked in cross section as shown in Figure 4.

For supporting the base plate 10, I provide a 20 pair of supporting elements S, which may be formed inexpensively of wood or any suitable composition. Each supporting element S has a flange 13, projecting from one side thereof and extending throughout the length thereof. 25

The ends of the flange 13 are received in the hooked flanges 12 as shown in Figures 2, 3 and 4.

The flanges 13 span the distance between the bottoms of the hooked flanges 12 and substantially fill the flanges 12, so as to provide an efficient support for the ends of the base plate 10 when it is assembled on the supporting elements S. 30

By extending the flange 13 throughout the length of the supporting element S, the flange 35 serves to reinforce and support the end of the base plate 10.

The shoulder 14 formed at the base of the flange 13 is of substantially the same width as the thickness of the base plate 10 as shown in 40 Figure 3. This provides a flush relationship between the upper surface of the base plate 10 and the upper surface of the supporting element S, and therefore gives a very neat appearance to the base assembly. 45

Likewise the ends of the flanges 13 are offset so that a flush relationship is maintained throughout at least half of the radius of the hooked flange 12, as shown in Figure 4, so that the major portion of the contour of the supporting elements S form continuations of the contour of the base plate 10. This gives a distinctiveness of design lacking with the usual types of supporting elements or handles, which extend only part way across the end of the base 50 55

plate, and which are usually less than one-fourth as long as the base plate is wide.

Means may be provided to positively retain the base plate 10 assembled relative to the supporting elements S instead of depending on the resiliency of the flanges 12, and the frictional fit between these flanges of the base plate and the flanges 13 of the supporting elements. For instance the bottom of the flange 12 may be indented as indicated at 15 in Figures 2 and 3 after the parts are assembled together, thus normally preventing any pulling apart of these parts thereafter.

As shown in Figure 5, the flange 13 may be cut away as indicated at 13a, thus using somewhat less material in the supporting element S, yet leaving sufficient stock at the ends of the flange to coact with the hooked flanges 13 of the base plate.

20 In Figure 6, I show a supporting element S', which instead of having a flange 13 is provided with a pair of dowel pins 13b. These are adapted to extend into rolled flanges 12a of the base plate 10 and may be retained therein in any suitable 25 manner.

In Figure 7, I illustrate retainer discs 16 for this purpose. The dowels 13b are preferably shouldered and have extensions 17 entering sockets 18 of the supporting elements S' as shown 30 in Figure 8.

A brad 19 may be used to pin the dowel in position if desired.

The support S', it will be noted, does not have any support for the base plate 10 intermediate the 35 dowel pins 13b as such support can be omitted there. The appliance A is of relatively light character and the plate 10 sufficiently heavy to withstand bending under the weight of the appliance, without the necessity of a support intermediate 40 the dowels 13b.

Some changes may be made in the construction and arrangement of the various parts of my appliance base, without departing from the real spirit and purpose of my invention, and it is my 45 intention to cover by my claims, any modified forms of structure or use of mechanical equivalents, which may be reasonably included within their scope.

I claim as my invention:

50 1. A base for electrical appliances and the like comprising a base plate and a pair of elongated supporting elements for supporting two opposite side edges thereof, said elongated supporting elements each having a flange on which said side edge of said base plate rests, said base plate having along each of its other two side edges a flange of less width than the height of said supporting elements, said flanges of said supporting elements extending between said flanges of said 55 base plate.

2. A base for electrical appliances and the like comprising a sheet metal plate and a pair of supporting elements for the ends thereof extending from one side of the plate to the other, said 60 supporting elements having means projecting at right angles therefrom for connection with said

plate, and said plate being formed to partially encircle said means sufficient to lock the projecting means within the encircling portion.

3. A base for electrical appliances and the like comprising a base plate and a pair of elongated 5 supporting elements for supporting two opposite side edges thereof, said elongated supporting elements each having a flange on which said side edge of said base plate rests, said base plate having along each of its other two side edges, a hooked flange, said flanges of said supporting elements extending between said hooked flanges of said base plate and having their ends seated therein.

4. A base for electrical appliances and the like comprising a base plate and a pair of elongated 10 supporting elements for supporting two opposite side edges thereof, said elongated supporting elements spanning said side edges, said base plate having along each of its other two side edges a flange, said supporting elements having 15 connecting parts extending between and being seated in said flanges of said base plate.

5. A base for electrical appliances and the like comprising a base plate having side flanges and a pair of elongated supporting elements for the 20 ends of said base plate, said supporting elements having means projecting under said base plate to support the base plate at the corners thereof with the top of the base plate substantially flush with the top of the supporting elements, said 25 means extending between said side flanges with the outer surfaces of said flanges substantially flush with the ends of said supporting elements.

6. In an appliance base, a base plate of rectangular shape, U-shaped flanges formed along 30 two opposite side edges thereof, a supporting element along each of the other side edges of said base element, and means projecting from said supporting element and into and substantially filling said flanges to support said base element 35 relative to a supporting surface.

7. In an appliance base, a sheet metal base element of rectangular shape, oppositely curved flanges formed along two opposite side edges thereof, a supporting element along each of the other side edges of said base element, projections 40 from said supporting element received in and positioned against the inner faces of said oppositely curved flanges to support said base element relative to a supporting surface, and means 45 to secure said projections therein.

8. A base for electrical appliances and the like comprising a base plate and a pair of supporting elements of different material for the marginal end edges thereof, said supporting elements being 50 of greater height than the over-all height of said base plate, said supporting elements having means projecting under and attached to said base plate to support the base plate relative thereto, said supporting elements being, along their tops, of 55 the same contour as the top of said base plate and forming flush-related continuations of the base plate and said base plate having its side edges provided with hooked flanges interlocking 60 with said supporting elements.

65 WILLIAM H. FISCHER.
